DELAYED-ACTION FUSE

Ben W. Sewell, Tulsa, Okla., assignor to the
United States of America as represented by the
Secretary of the Navy

Application April 15, 1947, Serial No. 741,452

2 Claims. (Cl. 102—80)

1

The present invention relates to a delayed action fuse for military missiles; more particularly to a fuse for projectiles used in destroying armored and concrete structures.

An object of the invention is to provide a delayed action fuse for all types of military missiles.

Another object of the invention is to provide a fuse in which the firing pin is cocked upon impact and afterwards fires the primer when the negative acceleration or deceleration of the projectile drops to a selected value as the missile is further retarded during penetration.

A further object of the invention is to provide a fuse which will permit a projectile to penetrate a considerable thickness of armor or concrete before the fuse explodes the bursting charge within the projectile.

Among the advantages of this invention is the simple construction of this fuse over devices of the prior art. Moreover, deterioration in storage is reduced, inasmuch as none of its mechanical parts other than detent springs, are under any strain prior to being fired and also because the fuse is completely sealed against the elements.

The advantages of the present invention will be best understood in connection with the accompanying drawings:

Fig. 1 is a detailed sectional view of a fuse embodying the invention taken through the axis of the fuse when in the unarmed condition.

Fig. 2 is a similar view of the fuse when the projectile is in flight.

Fig. 3 is a similar view of the fuse at the moment of impact of the projectile on the target.

Fig. 4 is a similar view of the fuse at an infinitesimally later time.

Fig. 5 is a similar view of the fuse at the moment of firing the primer.

In the preferred embodiment of the invention, the cylindrical fuse body 11 has an axial bore 12 extending from the rear to the forward edges of the detents 13. The right or rear end of the bore 12 is tapped to receive the primer holder 14 containing detonator or primer 15. Within the bore 12, the cylindrical firing pin 16 is housed in the cylindrical inertia sleeve 17 in a slide fit and locked to this sleeve by a shear wire 18. The shear wire 18 passes through the holes 19 of the sleeve and 23 of the firing pin, and each end of the wire is bent over in the annular groove 21 of the inertia sleeve 17. The rear face of sleeve 17 has a recess of greater diameter than the firing pin 16 to accommodate the segmental split ring 22. The internal diameter of ring 22 is less than the di-

2

ameter of firing pin 16, and the ring prevents the point 23 of the firing pin from reaching the primer 15.

The forward end of the fuse body 11 has a stepped circular recess 24. In the narrower portion of this recess 24 is located a resilient, conical Belleville washer 25 anchored in position by a retaining ring 26 which fits into the stepped or wider portion of the recess 24. An interior partition or flange 27 with an aperture of the same diameter as the interior of sleeve 17 separates recess 24 from the bore 12. Flange 27 serves to limit the throw of the Belleville washer. A flanged guide button 28 is mounted in the center 15 of the Belleville washer 25 and is equipped with a stud 29 projecting to the rear along the axis of the fuse. The stud 29 fits into a counter-sunk guide hole 30 in the forward end of the firing pin 16 to maintain the pin in alignment. Two or 20 more safety detents 13 bear on the sides of the firing pin 16 in order to prevent the inertia sleeve 17 from sliding forward prior to firing the projectile from a gun. Detents 13 are slideably mounted on helical springs 31 in the detent cups 25 32 and channels 33 radially located in the fuse body 11. The entire fuse assembly is inserted in a cylindrical metal cover 34 which is open at one end. The open end is then crimped over the rear base of the fuse body at 35.

30 Prior to a projectile being fired, the fuse is in the condition shown in Fig. 1. Firing pin 16 and sleeve 17 are locked together by shear wire 18. The point 23 of the firing pin 16 is prevented from approaching primer 15 by the split ring 22. The 35 Belleville washer 25 is in its uncocked position. Sleeve 17 cannot move, as it bears against the primer holder 14 at the rear and the detents 13 at the forward end. It is apparent that the fuse in the unarmed condition is absolutely safe with the firing pin separated from the primer by a split ring, locked by a shear wire and having its driving member, in this case the Belleville washer, uncocked. The only working parts which are stressed in any degree are the detent springs 31 40 which are under light compression in their extended position.

In the operation of the fuse the projectile containing it is first fired from a gun. Under the influence of the high speeds of rotation caused by 50 the rifling of the barrel, the detents 13 spin out, that is, they are moved radially outward in the channels 33 and detent cups 32 as shown in Fig. 2. During the flight of the projectile no other action occurs in the fuse mechanism.

55 The condition of the fuse at the instant of the

impact on a target is illustrated in Fig. 3. From the inertial forces resulting from the negative acceleration, firing pin 16 and inertia sleeve 17 move forward as a unit thereby flattening and cocking the resilient Belleville washer 25. In cocking the washer, the mass of both the firing pin 16 and sleeve 17 is required to overcome the peak resisting force of the washer 25. The firing pin, Belleville washer and guide button reach the limit of their travel at this stage but the inertia sleeve only partially completes its travel.

An infinitesimal fraction of a second later, the fuse attains the condition disclosed in Fig. 4. Due to inertia, sleeve 17 continues forward thereby shearing the shear wire 18. The segments of the split ring 22 are pushed out of the rear recess in the inertia sleeve by reaction against the relatively stationary firing pin 16. Sleeve 17 slides down the bore 12 until it is stopped by flange 27. Centrifugal force drives the segments of the split ring 22 outward against the walls of bore 12 where the segments will not interfere in later movement of the firing pin. The fuse which was armed by rotation upon leaving the gun barrel has now been cocked by impact upon a target.

At the moment of impact the negative acceleration (sometimes referred to as reverse setback) of the projectile starts at a maximum value and steadily decreases as the projectile penetrates the target and slows down due to the resistance encountered. The negative acceleration decreases to a selected value whereupon the inertial force of the firing pin 16 is no longer sufficient to hold the Belleville washer 25 in the cocked position. As is evident in Fig. 5, the flattened or cocked washer returns to the conical shape shown in Fig. 1 sharply driving the firing pin 16 to the rear toward the primer 15, and the guide button 28 reaches the flange 27 during this movement. The movement of the Belleville washer 25 is halted by the flange, but the firing pin continues to the rear under its own momentum. There are now no restraining members in the path of the firing pin, and its tip 23 is driven into the primer 15 firing the percussion mixture.

The action of the fuse is predetermined by selection of elements of proper mass in designing the fuse; that is, by varying the weight of the firing pin and the inertia sleeve or by varying the stiffness of the Belleville washer, it is possible to regulate the depth of penetration in a given material at which detonation of the projectile will occur. While various materials may be employed for the construction of this fuse, metal is preferred because of its strength. As an example, in designing a fuse which will be cocked at a negative acceleration of 2000 times that of gravity (2000 g) and detonate the projectile when this negative acceleration drops to 1500 times gravity (1500 g), a Belleville washer is selected which has a peak or cocking force of 19 pounds and a minimum holding force of 6 pounds, a firing pin weighing 0.004 pound, inertia sleeve weighing 0.008 pound together with a copper shear wire having a shearing strength of more than 5.5 pounds and less than 8.0 pounds. With this assembly, upon impact as in Fig. 3, the combined inertia force of the firing pin 16 and inertia sleeve 17 is 24 pounds which is ample to cock the Belleville washer against a resistance of 19 pounds.

The forces involved are calculated by the equation $F=ma$ where F represents force in pounds, m represents mass in pounds and a represents acceleration in units of gravity. Thus the firing pin weighing .004 pound multiplied by 2000 g

exerts a force of 8 pounds, and the sleeve with a mass of .008 pound times 2000 g exerts a force of 16 pounds, when the negative acceleration is 2000 times the acceleration of gravity.

5 The action shown in Fig. 4 is readily understood by recalling that the inertia sleeve is exerting a force of 16 pounds on a shear wire which has a shearing strength of between 5.5 and 8 pounds and therefore requires a total force of 11 to 16 pounds to shear the wire at both ends of hole 20 in firing pin 16.

10 In the stage illustrated in Fig. 5, the value of negative acceleration drops below 1500 g and the firing pin, which by then is alone holding the washer cocked, will exert a force of less than 6 pounds. Since this force is less than the designed minimum holding force of 6 pounds, the Belleville washer reacts and hurls the firing pin to the rear with a net force of about 13 pounds (19 pounds less the inertia force of approximately 6 pounds which is exerted by the firing pin in a forward direction).

15 The Belleville washer of the present example has a total travel of .050" between the relaxed or normal position and the cocked position. A gap of .025" is used between the point 23 of the firing pin and the forward end of the primer 15. Accordingly, the firing pin travel is in excess of .075" and all travel in excess of .050" is overtravel. The firing pin derives sufficient momentum to accomplish this overtravel and also to set off the primer from the force applied by the Belleville washer.

20 25 30 35 40 45 The fuse of the invention, although particularly intended for use against concrete fortifications, may be used with equal success against steel and other varieties of armor. In addition to the particular application shown for rotating projectiles, in place of the radial detents, the fuse could be readily adapted for other types of military missiles of the non-rotating kind by substituting another arming device. Fuses for bombs, mortar shells and rockets are obviously within the scope of the invention. Thus it is evident that the device disclosed is capable of a wide variety of applications as a delayed action fuse.

50 Accordingly, it is to be understood that the invention is limited only by the scope of the appended claims and not to the preferred embodiment disclosed.

What is claimed is:

1. In a delayed-action fuse, a fuse body provided with a longitudinal bore, a primer at the rear end of the bore, a firing pin assembled within and joined by a shear member to an inertia sleeve located inside the bore, a segmental ring located in a recess in the rear end of the sleeve and adapted to separate the firing pin and the primer, a safety detent extending radially into the bore to prevent forward movement of the sleeve and displaceable by centrifugal force, a resilient conical washer adjacent the forward end of the firing pin and adapted to be flattened by a force and maintained flat by a lesser force; whereby upon rotation the detent is displaced from the bore thereby arming the fuse, thereafter upon impact the inertia of said firing pin and sleeve assembly carries it forward to flatten the resilient washer with the sleeve continuing forward to shear the shear member and displace the segmental ring from said recess thereby cocking the fuse, and thereafter upon reduction of the negative acceleration to a predetermined value the resilient washer resumes its normal conical shape thereby

driving the firing pin into contact with the primer to detonate the fuse.

2. A fuse for a missile that spins when fired from an ordnance piece, and comprising a firing pin, a primer, spacing means holding said pin out of contact with said primer, a snap spring normally urging said pin toward said primer, locking means normally preventing movement of said pin toward said spring, but releasing said pin due to centrifugal force when the fuse spins, a slidable member guided by said pin, and a shear wire securing said slidable member to said pin but shearing off when the fuse is negatively accelerated, thereby releasing the slidable member to slide into the path of the locking means and prevent the return thereof, said movement of the slidable member also releasing the spacing means to move, due to centrifugal force, out of the way of the firing pin, whereby obstruction to the sudden re-

turn motion of the firing pin into the primer under the urging of the snap spring under further negative acceleration will be removed.
